Primary Examiner — Eric Goodman*Assistant Examiner* — Amy Wierenga(74) *Attorney, Agent, or Firm* — Leason Ellis LLP**CLAIM**

The ornamental design for an opaque mat with diamond pattern, as shown and described.

DESCRIPTION

FIG. 1 is a top plan view of the opaque mat with diamond pattern;

FIG. 2 is a side profile view thereof; the left side of the figure being representative of the top plan view of FIG. 1;

FIG. 3 is an enlarged detail view of area 3 circumscribed within or on FIG. 2; and,

FIG. 4 is an enlarged detail view of area 4 circumscribed within or on FIG. 1.

The portions of the opaque mat with diamond pattern shown in broken lines form no part of the claimed design.

See application file for complete search history.
